WEB FEEDING MECHANISM FOR CASH
REGISTERS AND THE LIKEFrank R. Werner, Dayton, Ohio, assignor to The
National Cash Register Company, Dayton,
Ohio, a corporation of Maryland

Application August 25, 1948, Serial No. 46,165

10 Claims. (Cl. 164—84.5)

1

This invention relates to improvements in web feeding mechanisms for cash registers and calculating machines.

The object of the invention is to provide an improved printing mechanism, and particularly the mechanisms for controlling the operation of web feeding mechanisms.

A specific object of the invention is to provide a web feeding mechanism having tension rollers which grip the web at both sides thereof to facilitate the tearing of the web from either the right or the left.

Another specific object of the invention is to provide a web feed mechanism with tension rollers, one gripping the web at each edge thereof, and each tension roller being independently actuated by a resilient means so that each tension roller can effect an independent gripping of the web.

Another specific object of the invention is to provide a receipt printing mechanism with a stationary tear-off knife, and to provide the web feeding mechanism with two independently operable tension rollers which are adapted to grip the web at each edge thereof so that, when the operator tears the receipt from the web by pulling the web against the stationary tear-off knife, the operator may tear either from the right or from the left.

Another object of the invention is to provide a novel on-and-off means whereby the operator may throw the web feeding and printing mechanism on or off at will.

Still another object of the invention is to provide a web shifting mechanism which is simple in construction and operation, whereby the web may be shifted from a reading position into a printing position, and vice versa.

With these and incidental objects in view, the invention includes certain novel features of construction and combinations of parts, a preferred form or embodiment of which is hereinafter described with reference to the drawings which accompany and form a part of this specification.

Of said drawings:

Fig. 1 is a perspective view of the machine.

Fig. 2 is a detail view of the receipt web feeding mechanism.

Fig. 3 is a left side elevation of the machine, showing the printer mechanism.

Fig. 4 is a detail view of the on-and-off knob, together with certain mechanism for controlling the operation of the printing hammer for the issuing receipt.

Fig. 5 is a top plan view of the web feeding

mechanism, and the "on and off" controls therefor.

The invention is shown applied to a machine of the type illustrated in United States Patent No. 2,209,763, issued to E. Breitling on July 30, 1940.

Machines of the type illustrated in said patent are usually provided with a series of settable levers 71, 117 and 200 (Fig. 1) and each lever is geared to a type wheel for printing data upon an issuing receipt. Indicators 80 and 286 of the usual construction are provided. The machine is also provided with release keys 210, and special counters 325. The mechanism is enclosed in a cabinet 34, resting on a cash drawer base 33.

An electro printing device is provided for printing various data of a descriptive or advertising nature upon the face of the issuing strip. The type wheels are inked by an endless ribbon supported by a removable frame, which may be easily and quickly removed from the machine when it is desired to change or adjust the inking ribbon. An ink well is provided to constantly re-ink the ribbon. The electro printing and receipt feeding mechanism may be disabled when desired by means of a manipulative device which projects through the cabinet of the machine near its left side.

Printing mechanism

The machine is provided with a printing mechanism mounted on the left side frame 31, which printing mechanism records data on a receipt 470 (Fig. 3).

The receipt paper is fed from a supply roll 473 (Fig. 3), rotatably mounted on a stud 474, carried by the left side frame 31. The web of the receipt paper 475 is fed from the supply roll 473 around an ink well 476 and over a guard 471, between feed rollers 510, 511, and 512, 512 hereinafter described (see also Fig. 5), and through a chute 478 (see also Fig. 1). A stationary knife 469, mounted on the chute 478, is provided for tearing off the receipt 470 after the receipt has been issued from the machine.

An endless ribbon 479 is provided for expediting the printing of the data from a group of type wheels mounted on the stud 92, from manually settable date printing wheels, and from type wheels to identify the machine by a number or symbol, mounted on a stud 497.

Receipt printing mechanism

To record the impressions on the receipt paper from the type carriers on the studs 92 and 497, a

hammer 480 (see Figs. 3 and 4) is provided. The hammer 480 is provided with a platen 481, for printing from the type carriers on the stud 92, and a platen 482 for printing from the type wheels (not shown) on the stud 497. The hammer 480 is notched, to receive the forward end of an arm 485 (Fig. 4), and a stud 486, extending through the hammer 480 and the free end of the arm 485, provides a pivot point for the hammer 480. The arm 485 is pivoted on a stud 487 carried by the side frame 31 of the machine. The arm 485 has, mounted thereon, a square stud 488, which normally lies in the path of a second square stud 495 (see Fig. 4) carried by the forward end of a link 496. The square stud 495 is normally engaged by a lever 489 pivoted on the stud 487, the lower end of which lever is provided with an antifriction roller 490, held in engagement with a cam 491, on a cam shaft 37, by a spring 492.

Operation of the machine with the square stud 495 overlying the square stud 488 operates the printing hammer 480 in the following manner. Counterclockwise rotation of the cam 491 rocks, by engagement with the antifriction roller 490, the lever 489 clockwise against the action of the spring 492. Clockwise rotation of the lever 489 carries the stud 495 against the stud 488, thus rocking the arm 485 clockwise to lower the platens 481 and 482 to carry the web 475 and the ribbon 479 against the type carriers to make an impression on the receipt paper. After the impression has been made, and when the cam 491 passes beyond the roller 490, the spring 492 restores the hammer 480 into its original position.

The hammer 480 is provided with a guide slot 493 engaging a stud 494 carried by the left side frame 31. The slot 493, cooperating with the stud 494, guides the hammer in a vertical path when the arm 485 is rocked clockwise to make impressions.

The square stud 495 is movably mounted with the link 496 for disabling the printing hammer when desired. When moved leftwardly from the position shown in Fig. 4, the stud 495 is in its disabled position, and therefore, when the cam 491 rocks the lever 489, the stud 495 does not engage the stud 488; therefore the arm 485 is not operated. When it is desired to operate the hammer 480, the square stud 495 is moved to the right (as shown in Fig. 4) until it comes over the stud 488 in the manner described hereinafter.

Receipt feed and electro mechanisms

After the impression has been made by the hammer 480, the receipt paper web 475 is fed forwardly through the opening in the chute 478, and, while said receipt web is being fed, an electro device prints various data of descriptive, or advertising, nature on the face of the succeeding receipt. The receipt feeding and electro mechanism will now be described.

Referring to Figs. 2 and 3, secured to the shaft 37 is a partial gear 501, the teeth of which cooperate with the teeth in a full gear 502 loose on a stud 503, and said gear 502 meshes with a full gear 504, loose on the stud 92. The gear 504 meshes with a full gear 505 rotatably supported by the beforementioned stud 497 secured in the side frame 31. The gear 505 meshes with a gear 506 secured to a shaft 507 mounted between the side frame 31 and a printer plate 498. Also secured to the shaft 507 is a gear 508 meshing with

5 a gear 509 rotatably mounted on the stud 497. The gears 505 and 509 are located adjacent the edges of the receipt paper web 475. Secured to the side of the gear 505 is a feed roller 510, and secured to the side of the gear 509 is a feed roller 511. The feed rollers 510 and 511, coaxing with pressure rollers 512, 512, one provided to engage each of the feed rollers, cooperate to feed the receipt web 475. Since the feed rollers and the pressure rollers engage the receipt paper web at its edges, the receipt paper will be fed through the machine in a straight line. Each pressure roller 512 is independently mounted on a bell crank 513 pivotally mounted on the stud 494 mounted on the side frame 31. A link 514 connects each bell crank 513 to a rod 515. The ends of the rod 515 are loosely engaged with the links 514 to permit independent action of each link 514 and each bell crank 513, so that the pressure rollers 512 can receive independent movement, so that a firm contact will be made with their respective feed rollers. A single spring 516 is connected at one end to the rod 515 midway between its two ends and at its other end to a rod 517. The rod 517 is carried by two arms 518, 518, which arms are connected together by a yoke 519. The yoke 519 supports a printing platen 520, which platen is provided to take impressions from a rotatable electro roll 521. The yoke 519 is held against an adjustable screw 522, carried by a bar 5242 connecting an arm 524 and an arm 5241, both arms being pivoted on a stud 526. A spring 523, stretched between a stud on one arm 518 and a stud in the arm 524, maintains the yoke 519 in contact with the adjustable screw 522. A spring 527, connected to a stud on the arm 524, maintains a stud 525 on said arm 524 in engagement with a cam plate 528 rotatably mounted on a stud 530.

40 The cam 528, in cooperation with the stud 525, maintains the arm 524 and the adjusting screw 522 in such contact with the yoke 519 as to maintain the electro printing platen 520 in printing position. When the parts just described are in the position shown in Fig. 3, under control of the cam plate 528, the rod 517 is located in slots 531 in such relation to the left-hand ends of said slots as to permit the spring 516, acting through links 514, to independently maintain the pressure rollers 512, 512 in contact with their respective feed rollers 510 and 511.

45 With the pressure rollers 512, 512 resiliently held against the feed rollers 510 and 511, when the machine is operated, the main cam shaft 37, through the gears 501, 502, 504, 505, 506, 508, and 509 and the feed rollers 510 and 511, feeds the receipt paper out of the machine. During this operation, the gear 502 rotates the electro 50 roll 521 to cause the advertising matter to be printed on the receipt paper.

50 In order to provide time for the printing hammer 480 to take its impression before the receipt is fed out of the machine, the gear 501 has a section of its teeth omitted, and a plate 532 is secured thereto, which, in cooperation with the cut-away portion 533 on the gear 502, maintains the gear 502 against rotation until the plate 532 passes beyond the cut-away portion 533. After the cut-away portion 533 is free from the gear 502, the partial gear 501, acting through the train of gears 502 to 509, rotates the feeding disks 510 and 511. During this operation, gear 502 rotates the electro cylinder to make the impressions on the receipt paper for the next receipt to be issued.

Printer and feed throw-off

When it is desired to operate the machine without issuing a receipt, the printer plate 480 and the feed mechanism are disabled, by rotating the cam plate 528 prior to a machine operation. To facilitate the adjustment of the cam plate 528, a knob 536 is provided thereon, which knob projects through the cabinet of the machine, as illustrated in Fig. 1. The full-line position of the knob 536 (in Fig. 4) indicates the position which the cam plate assumes when the printer hammer and the feed mechanism are operated. As shown in this figure, the square stud 495 lies over the square stud 488, and therefore, when the machine is operated, the square stud 495, acting on the square stud 488, operates the printing hammer in the manner described above. If it is desired to disable the printing mechanism, the operator moves the knob 536 to the dot-and-dash line position shown in Fig. 4. This rotates the cam plate 528 and causes a cam surface 537 thereon to coat with the stud 525 and allow the movement of the arm 524 counter-clockwise under action of the spring 527. The rotation of the cam plate 528 is arrested when a node 539 thereon comes into contact with the stud 525. Counter-clockwise movement of the arm 524, through the spring 523, lifts the arms 518 to move the electro platen 520 into ineffective position. Simultaneously, the arms 518, acting on the rod 517, shift the links 514 leftwardly (Fig. 3) to rock the bell cranks 513 counter-clockwise to raise the pressure rollers 512, 512 out of engaging position with the feed rollers 510 and 511. Also simultaneously with the counter-clockwise movement of the rod 517, the link 496 is moved leftwardly to move the square stud 495 from the position shown in Fig. 4 to the position in which the square stud 495 no longer overlies the square stud 488. Subsequent operation of the machine when the main cam shaft 37 is rotated causes the lever 489 to rock the square stud 495 idly, and therefore the printing hammer 480 will not be operated to make an impression. Also the operation of the feed rollers 510 and 511 is idle, since the tension rollers 512 are not engaged therewith.

While the form of mechanism shown and described herein is admirably adapted to fulfill the objects primarily stated, it is to be understood that it is not intended to confine the invention to one form or embodiment disclosed herein, for it is susceptible of embodiment in various other forms.

What is claimed is:

1. In a web feed mechanism for a machine of the class described, the combination of feed rollers, tension rollers coacting with the web and the feed rollers adjacent the edges of the web, a separate support for each tension roller, an independently operable means connected to each tension roller support to move the respective tension rollers into coacting positions, a rod loosely connecting the independently operable means, and a single spring, one end thereof being connected to the rod and the other end thereof being connected to a support therefor, said spring being biased to actuate the said means.

2. In a web feed mechanism for a machine of the class described, the combination of feed rollers, tension rollers coacting with the web and the feed rollers adjacent the edges of the web, a separate support for each tension roller, a link connected to each tension roller support, a rod loosely connecting the free ends of the links to

allow independent movement of the links, and a single spring, one end thereof being connected to the rod and the other end being connected to a support therefor, said spring biased to move said links and tension roller supports separately to independently move the tension rollers into coacting positions.

3. In a web feed mechanism for a machine of the class described, the combination of feed rollers, tension rollers coacting with the web and the feed rollers adjacent the edges of the web, a separate support for each tension roller, a link connected to each tension roller support, means loosely connecting the links whereby the links can move independently of each other to thereby move the tension rollers into coacting positions independently of each other, and a single spring one end thereof operatively attached to the connecting means, and the other end attached to a support, said spring biased to actuate the connecting means.

4. In a web feed mechanism for a machine of the class described, the combination of feed rollers; tension rollers coacting with the web and the feed rollers adjacent the edges of the web; a separate support for each tension roller; independently operable means connected to each tension roller support, a rod loosely connecting the independently operable means, a single spring, one end thereof being connected to the rod, and the other end thereof being connected to a support, said spring being biased to actuate the rod and the independently operable means to move the respective tension rollers into coacting positions; and a stationary tear-off knife adjacent the path of travel of the web, said tension rollers gripping the web at both edges, acting to hold the web to permit the web to be torn from either side against the stationary tear-off knife.

5. In a web feed mechanism for a machine of the class described, the combination of feed rollers; tension rollers coacting with the web and the feed rollers adjacent the edges of the web; a separate support for each tension roller; a link connected to each tension roller support; means loosely connecting the links whereby the links can move independently of each other to thereby move the tension rollers into coacting positions independently of each other; a single spring having one end connected to the connecting means and the other end connected to a support, said spring biased to actuate the connecting means; and a stationary tear-off knife adjacent the path of travel of the web, said tension rollers gripping the web at both edges and acting to hold the web to permit the web to be torn from either side against the stationary tear-off knife.

6. In a web feed mechanism for a machine of the class described, the combination of feed rollers; tension rollers coacting with the web and the feed rollers adjacent the edges of the web; a separate support for each tension roller; a link connected to each support; a yoke including two arms, each arm having an opening; a rod projecting into the holes of the arms and into slots in said links, a second rod loosely connecting the free ends of the links, said loose connection and slots providing means whereby the links can move independently of each other to thereby move the tension rollers to coacting positions independently of each other; and a spring stretched between the rods to actuate the links.

7. In a web feeding mechanism for a machine of the class described, the combination of feed rollers; tension rollers coacting with the web

and the feed rollers adjacent the edges of the web; a separate support for each tension roller, said supports being independently operable; a link connected to each tension roller support to move the respective tension rollers into coacting position; a yoke including two arms, each arm having an opening; a rod projecting into the openings of the arms and into the slots of said links, a second rod loosely connecting the free ends of the links, said loose connection and slots providing means whereby the links can move independently of each other to thereby move the tension rollers into coacting positions independently of each other; a spring stretched between said rods to actuate the links, said yoke adjustable from a position in which the tension rollers are resiliently held in coacting position with the feed rollers to a position in which said tension rollers are moved out of coacting position with the feed rollers; an arm coacting with the yoke to determine the position of the yoke; and a cam to move the arm into one or the other of its two positions.

8. In a machine of the class described, the combination of feed rollers; tension rollers independently mounted on a common axis and each roller independently movable into coacting position with the web adjacent the edges thereof and the feed rollers to feed the web; a separate means for each tension roller to urge the tension rollers into said coacting position; a single resilient means to actuate both of said means; a cam settable to two positions; an arm controlled by the cam to assume a different setting for each setting of the cam; and connecting means between the arm and the tension rollers, whereby the separate resilient means are set in accordance with the setting of the arm and the cam, said tension rollers held in feeding position when the cam is set into one position and out of feeding position when said cam is set into its other position.

9. In a machine of the class described, the combination of feed rollers; tension rollers independently mounted on a common axis and said rollers independently movable, from a position in which they coact with the feed rollers to feed the web into a position in which they do not coact with the feed rollers to thereby prevent feeding

5
10
15
20
25

of the web; a separate operable connection to urge each tension roller into said coacting position; a single resilient means to actuate both of said connections; connections to disable the operable connections; and a manipulative device to determine the position of the connections.

10. In a machine of the class described, the combination of feed rollers; tension rollers, movable from a position in which they coact with the feed rollers to feed the web into a position in which they do not coact with the feed rollers to thereby prevent feeding of the web; a link to urge each tension roller into said coacting position; a rod loosely attached to said links; a single spring attached to the rod and to a support means for said links to actuate said links; a two-armed yoke; a pin-and-slot connection between each arm and each link; connections including a cam arm; and a cam to control the position of the yoke whereby the yoke is positioned in one of two positions, said yoke determining the position of the links whereby the tension rollers are moved into effective or ineffective position.
